US0D1029898S

(12) **United States Design Patent** (10) **Patent No.:** **US D1,029,898 S**
(45) **Date of Patent:** **** Jun. 4, 2024**

(54) **CUTTING TOOL INSERT**

(71) Applicant: **Sumitomo Electric Hardmetal Corp.**,
Itami (JP)

(72) Inventor: **Tangwei Zhao**, Itami (JP)

(73) Assignee: **SUMITOMO ELECTRIC
HARDMETAL CORP.**, Itami (JP)

(**) Term: **15 Years**

(21) Appl. No.: **29/835,688**

(22) Filed: **Apr. 21, 2022**

(51) LOC (14) Cl. **15-09**

(52) U.S. Cl.

USPC **D15/139**

(57) **CLAIM**

The ornamental design for a cutting tool insert, as shown and described.

DESCRIPTION

FIG. 1 is a front view of a cutting tool insert in accordance with my design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is a cross sectional view taken along line 8-8 of FIG. 1;

FIG. 9 is a cross sectional view taken along line 9-9 of FIG. 1; and,

FIG. 10 is a perspective view showing the cutting tool insert in a state of use.

The broken lines shown in the drawings represent portions of the cutting tool insert that form no part of the claimed design.

1 Claim, 10 Drawing Sheets
